THROTTLE CONTROL FOR LOCOMOTIVES
OR THE LIKE

William F. Kromer, Sharpsburg, Pa., assignor to
H. K. Porter Company, Inc., Pittsburgh, Pa., a
corporation of Pennsylvania

Application February 10, 1944, Serial No. 521,797

4 Claims. (Cl. 290—4)

This invention relates to control apparatus for a vehicle such as a locomotive having two engines operating propulsion drives independently.

It is customary in constructing locomotives driven by internal-combustion engines, particularly in the larger sizes, to provide a frame with front and rear trucks, and to drive the wheels of the two trucks from separate engines usually placed ahead of and behind the operator's cab. Under normal conditions, it is satisfactory to control the two engines as a single unit. Under special conditions, however, as where the wheels of one truck rest on a bad spot in a rail, it is desirable to accelerate one engine to a speed above that of the other in order to apply a greater tractive effort through the truck resting on the sound portion of the rail thereby avoiding excessive slippage of the wheels of the other truck which might occur as a result of their engagement with the bad spot.

I have invented a novel form of control device particularly suited for locomotives having independent drives for the two trucks thereof. In a preferred embodiment, my invention comprises a pair of members disposed coaxially and mounted for rotation, each having a connection to the fuel-supply mechanism of one engine. These members may conveniently be a tube and a shaft disposed therein. They normally move together by virtue of an adjustable connection in the form of an equalizing lever, the shaft being provided with a throttle lever. The equalizing lever permits the engine whose fuel-supply mechanism is controlled by the tube to be set for operation at a speed above or below that of the other engine when the throttle lever is advanced. The invention is particularly suited for use on electrically driven locomotives in which the internal-combustion engines drive separate generators supplying motors mounted on the two trucks.

Other details, novel features and advantages of the invention will be made apparent during the following complete description which refers to the accompanying drawings illustrating the preferred embodiment. In the drawings,

Figure 1 is a plan view of the control apparatus;

Figure 2 is a sectional view therethrough taken along the plane of line II—II of Figure 1, showing parts in elevation;

Figure 3 is a partial section taken axially through the tube and shaft and the throttle and equalizing levers;

Figures 4, 5 and 6 are horizontal sections taken through the apparatus along the planes of lines IV—IV, V—V and VI—VI, respectively;

Figure 7 is a diagrammatic floor plan of a locomotive showing the engines and generators thereof and the relation of the invention thereto.

Referring in detail to the drawings, the con-

trol apparatus of my invention indicated generally at 10 is mounted on a supporting standard 11 fabricated from plates and including a base 12, side plates 13 and web plate 13a. The apparatus 10 is mounted, as shown in Figure 7, in the operator's cab 14 of a locomotive 15 having internal-combustion engines 16 and 17 driving generators 18 and 19, respectively. Each generator supplies current to the motor (not shown) driving one of the two trucks of the locomotives.

A quadrant plate 13b extends outwardly in a horizontal plane from the web plate 13a near the upper end thereof. A shaft 20 is journaled at its upper end in the plate 13b and at its lower end in a thrust bearing 21 secured to the base 12. A throttle lever 22 is pinned to the upper end of the shaft 20 and is provided with a detent 23 pivoted on a stud 23a and adapted to enter a notch in the periphery of the quadrant plate 13b, as shown in Figure 1. A release linkage for the detent 23 includes a push button 24 in the end of the lever, from which a push rod 25 extends to a crank arm on the detent. A crank disc 26 is secured to the shaft adjacent the lower end thereof and is connected to a Bowden cable 27 extending to the fuel injector of the engine 17. A tube 28 surrounds the shaft 20 and extends from near the lower end to a point spaced below the upper end thereof. The tube is conveniently journaled on sleeves 29 and 30 secured to the shaft. A crank disc 31 secured to the lower end of the tube 28 is connected to a Bowden cable 32 extending from the control apparatus 10 to the fuel injector of the engine 16.

An equalizing lever 33 comprises an arm 34 secured to the upper end of the tube 28 and a crank plate 35 secured to the sleeve 29. A toothed segment 36 is formed at one end of the plate 35. A toothed slide 37 is movable along the arm 34 for meshing engagement with the segment 36. The slide 37 is actuated by a lever 38 pivoted to the arm 34 and a link 39. A spring 40 normally urges the slide 37 into meshing engagement with the segment 36.

It will be apparent that the equalizing lever serves to lock the tube 28 to the shaft 20 for rotation as a unit. At the same time, the equalizing lever provides means for quickly and easily changing the angular adjustment of the tube 28 relative to the shaft 20. Since the angular relation of the tube to the shaft determines the relative speeds to which the engines 16 and 17 accelerate on movement of the throttle lever 22, it will be understood that the equalizing lever permits the engine 16 to be run at a speed above or below that of the engine 17. Index marks 41 are placed on the segment 36 and slide 37 to show when the tube 28 is in such position relative to the shaft 20 that both engines will operate at the

same speed. The desired advance or retardation in the speed of the engine 16 relative to that of the engine 17 may be obtained simply by shifting the arm 34 relative to the plate 35 after disengaging the slide 37 from the segment 36. This adjustment is preferably made while the lever 22 is in idling position, as illustrated in Figure 1, but may also be made even after the lever has been advanced from the idling position. In either case, after the equalizing lever has been shifted from neutral position, a constant differential is maintained between the settings of the fuel injectors of the two engines until the equalizing lever is restored to neutral position.

The plate 35 has an arm 42 projecting through a hole 43 in the web plate 13a and slotted as at 44. A lever 45 extends from the crank arm 46 of an accelerating switch 47 through the opening 43 and is slotted as at 45a. A pivot pin 42a secured to the arm 42 extends through the slots 44 and 45a so that angular movement of the plate 35 effects similar movement of the lever 45. As shown in the drawings, the lever 45 fits on the shaft on which the crank arm 46 is mounted and is adjustably secured to the latter by a bolt 46a extending through a slot 49 in the lever.

The switch 47 is of known construction and serves first to connect the generators 18 and 19 to the truck motors and then to alter the connections of the generator field circuits to accelerate the motors. By virtue of the construction described, the switch is advanced as the throttle lever 22 is moved. The adjustment of the equalizing lever does not change the relation between the switch 47 and the throttle lever 22. The net result is that the engine 16 is always accelerated in timed relation to the operation of the switch 47 while the engine 17 may be temporarily set by adjustment of the equalizing lever 33 to run faster or slower than the engine 16.

A removable cover 48 secured to the standard 11 encloses the switch 47 and the back of the web plate 13a. A reversing controller 49 is mounted on the standard 11 near the top of the plate 13a. It includes a vertical shaft 50 and an operating lever 51. The shaft 50 extends through the quadrant plate 13b and is provided with a cylindrical segment 52 having a slot 53. The shaft 20 is provided with a cylindrical segment 54 positioned so that its path intersects that of the segment 52. When the lever 51 is in neutral position, the slot 53 is in alignment with the path of the segment 54. The segment 52, furthermore, is of such arcuate length that it clears the path of the segment 54 when the lever 51 is shifted to either extreme position for establishing connections for either forward or reverse movement of the locomotive.

The reversing controller 49 like the switch 47 is of known construction and requires no further detailed description. It will be evident that the interlocking segments 52 and 54 prevent the throttle lever 22 from being advanced unless the lever of the reversing controller is in neutral or one of its extreme positions. Similarly, the arcuate length of the segment 54 is such that it prevents shifting of the reversing controller at any time except when the lever 22 is in idling position, at which time the relation of the interlocking segments is as shown in Figure 4.

It will be apparent from the foregoing descrip-

tion and explanation that my invention provides a control device particularly suited for locomotives or the like driven by two independent power plants, which has numerous important advantages. As already explained, the equalizing lever makes it possible to set one engine for operation at a speed higher or lower than that of the other, thereby applying a greater tractive effort through one truck in case the wheels of the other tend to slip by reason of a bad condition of the rail. The adjustment necessary to set up a differential between the speeds of the two engines may be made quickly and easily and does not interfere with the normal operation of the throttle lever or the accelerating switch. In addition, the invention provides interlocking between the throttle lever and reversing controller to prevent improper operation thereof. The invention is of simple construction and the operation thereof does not introduce any additional complications into the usual duties of the locomotive operator beyond the mere adjustment and restoration of the equalizing lever which may be accomplished in a few seconds.

Although I have illustrated and described but a preferred embodiment of the invention, it will be recognized that changes in the construction or the arrangement of the parts may be made without departing from the spirit of the invention or the scope of the appended claims.

I claim:

1. A throttle control for a locomotive or the like having two independent power plants each including an engine, a generator and a motor, said control comprising a switch for controlling the speed of said motors, a pair of rotatably mounted members each having means connected thereto for controlling the speed of one of said engines, means for adjustably securing said members together for simultaneous rotation in a predetermined angular relation, and means whereby rotation of said members actuates said switch.

2. A throttle control for a locomotive or the like having two independent power plants each including an engine, a generator and a motor, said control comprising a switch for controlling the speed of said motors, a shaft and a tube disposed coaxially and mounted for rotation, means on both the shaft and tube for controlling the speed of one engine, means on the shaft for actuating the switch and means for adjustably securing the shaft to the tube for rotation therewith in a predetermined angular relation.

3. A throttle control for a locomotive or the like having two independent power plants each including an engine, a generator and a motor, said control comprising a switch for varying the speed of said motors, a manually operable shaft having a member thereon for operating the speed control of one of the engines, said shaft also having means thereon for actuating said switch, a tube rotatable on said shaft and having a member thereon for operating the speed control of the other engine, and means releasably locking the tube to the shaft for rotation therewith in a selected angular relation thereto.

4. The apparatus defined by claim 3 characterized by said last-mentioned means being selectively engageable with said switch-actuating means.

WILLIAM F. KROMER.
